(57) **CLAIM**

The ornamental design for a speaker unit for watercraft, as shown and described.

DESCRIPTION

FIG. 1 is a front elevational view of a speaker unit for watercraft showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear left perspective view thereof;

FIG. 8 is a front right perspective view thereof; and,

FIG. 9 is a rear right perspective view thereof.

The subject speaker unit is installed onto watercrafts for music appreciation.
